UNITED STATES PATENT OFFICE

JOHN L. SMITH, OF SHREVEPORT, LOUISIANA

DESIGN FOR A FILLING STATION

Application filed October 7, 1930. Serial No. 37,168. Term of patent 14 years.

To all whom it may concern:

Be it known that I, JOHN L. SMITH, a citizen of the United States, residing at Shreveport, in the parish of Caddo and State of Louisiana, have invented a new, original, and ornamental Design for a Filling Station, of which the following is a specification, reference being had to the accompanying drawing, forming part thereof.

The figure in the drawing is a perspective view of a filling station showing my design.

I claim:—

The ornamental design for a filling station, as shown.

JOHN L. SMITH.
